UNITED STATES PATENT OFFICE.

MORTIMER ISAACS, OF HELENA, ARKANSAS.

DESIGN FOR A ROAD SIGN.

Application filed April 6, 1923. Serial No. 5,708. Term of patent 14 years.

To all whom it may concern:

Be it known that I, MORTIMER ISAACS, a citizen of the United States, residing at Helena, in the county of Phillips and State of Arkansas, have invented a new, original, and ornamental Design for Road Signs, of which the following is a specification, reference being had to the accompanying drawing, forming a part thereof.

Fig. 1 is a front elevation of a road sign, showing my new design.

Fig. 2 is a plan view thereof.

I claim:

The ornamental design for a road sign, as shown.

MORTIMER ISAACS.
